FURNACE ROOF STRUCTURE

Levi S. Longenecker, Mount Lebanon, Pa.

Application March 17, 1949, Serial No. 81,889

17 Claims. (Cl. 110—99)

1

This invention relates to furnace roof structures and more particularly to structures in which the refractory roof blocks are suspended in groups or bundles from overhead support beams.

In Patent 1,913,168 issued to me on June 6, 1933, I disclose a furnace roof structure of this type in which the refractory roof blocks are individually supported by interengaging sections of cantilever beams which are anchored to and extend in opposite directions from overhead I-beam supports. The group or bundle of blocks supported by one such cantilever beam abuts and also counterbalances the group or bundle supported by the opposed cantilever beam; each such cantilever beam having its own support by means of which it is anchored to the I-beam.

In Patent 2,126,901 issued to me on August 16, 1938, I disclose the same type of cantilever suspension, but in this patent each roof block is provided with an upwardly projecting extension for receiving its metal hanger section which forms part of the cantilever beam by which such block is supported. These upwardly projecting extensions place these metal hanger sections further from the heat of the furnace chamber than in the construction shown in Patent 1,913,168.

One object of this invention is to produce a furnace roof structure utilizing the type of cantilever suspension disclosed in my said patents but in which the metal hanger sections of such suspension are spaced much further from the heat of the furnace chamber than even those of the structure of Patent 2,126,901.

Another object is to produce improved refractory elements for a suspended furnace roof structure.

Another object is to produce an improved one-piece metal hanger for supporting two opposed cantilever beams from an overhead I-beam.

Another object is to produce a cast metal hanger for supporting from the lower flange of an overhead I-beam an assembly comprising oppositely extending cantilever beams and refractory blocks supported thereby, which is shiftable laterally of such beam flange to compensate for crookedness of the beam and thickness variations in such refractory blocks.

A further object is to produce a three-part refractory element in which such parts are so interlocked that they can be handled as a single unit.

A further object is to produce an improved suspended interlocking furnace roof structure of the general type disclosed in my said patents, but in which the refractory portions of the roof

2

structure can be produced more cheaply than those of either of said patents and in which the cantilever support beams are better protected from furnace chamber temperatures than in the structures of my said patents.

Another object is to produce an improved roof refractory of the interlocking block type such as broadly disclosed in my said prior patents.

These and other objects I attain by means of the structure described in the specification and illustrated in the drawings accompanying and forming part of this application.

In the drawings:

Figure 1 is an end elevational view of a furnace roof structure embodying this invention;

Fig. 2 is a top plan view of that portion of the furnace structure disclosed in Fig. 1;

Fig. 3 is an elevational view taken on line III—III of Fig. 1;

Figs. 4 and 5 are isometric perspective views of one of the roof blocks of this invention looking toward opposite sides thereof;

Fig. 6 is an isometric perspective view of a ceramic hanger block of this invention;

Fig. 7 is an isometric perspective view of an assembly of two roof blocks and one ceramic hanger and comprises one complete refractory unit, the parts of which are interlocked and capable of being handled as one element;

Fig. 8 is a top plan view of a one-piece cast metal hanger element for supporting two opposed cantilever beams from an overhead I-beam;

Fig. 9 is a front elevational view of such hanger element;

Fig. 10 is a sectional view taken on line X—X of Fig. 8;

Fig. 11 is an end view looking from line XI—XI on Fig. 8;

Fig. 12 is a view similar to Fig. 9 of the hanger element and shows in place therein upper portions of four ceramic hanger tiles such as disclosed in Fig. 6;

Fig. 13 is an enlarged view of a portion of Fig. 1;

Fig. 14 is a view looking toward the left side of Fig. 13;

Figs. 15, 16 and 17 are detail views of one of the metal hanger members such as form a single element or section of one of the cantilever beams utilized in the structure of this invention. These views include the upper portion of a ceramic hanger tile of Fig. 6 and show the application of such hanger member to such a tile;

Fig. 18 is an isometric perspective view of a shouldered roof block used in my roof structure;

Fig. 19 is an isometric perspective view of a metal spacing member such as used above one such shouldered block;

Fig. 20 is a sectional view taken on line XX—XX of Fig. 1;

Fig. 21 is a top plan view in modified form of a metal hanger for supporting or anchoring opposed cantilever beams to an overhead I-beam;

Fig. 22 is a front elevational view of the hanger of Fig. 21;

Fig. 23 is an isometric perspective view of a ceramic tile for use in connection with the hanger member of Figs. 21 and 22;

Fig. 24 is an isometric perspective view of an assembly comprising a hanger tile of Fig. 23 and four roof tiles of Fig. 4 or 5;

Fig. 25 is a view similar to Fig. 13 but shows the hanger of Figs. 21 and 22 and two assemblies such as disclosed in Fig. 24;

Fig. 26 is a view looking toward the left of Fig. 25;

Fig. 27 is a top plan view of the roof portion shown in Fig. 25; and

Fig. 28 is a view taken on line XXVIII—XXVIII of Fig. 25.

By referring to Figs. 1, 2 and 3 of the drawings, it will be seen that the roof structure of this invention as in the structures of my said patents makes use of opposed sectional cantilever beams for supporting the refractories from I-beams forming part of the furnace superstructure.

In such patents, each refractory unit comprises but one regular size refractory roof block and this is independently suspended by one element of a sectional cantilever beam. In the present structure, however, each refractory unit comprises an assembly of three refractory blocks which can be handled as a unit and includes two half size roof blocks and a hanger block.

In the present structure, each pair of opposed sectional cantilever beams has its fixed ends attached to a single cast metal member which is supported on the lower flange of an overhead I-beam and is constructed so that it can be adjusted laterally of such flange in order that the refractories supported by and depending from such cantilever beams anchored thereto can be shifted laterally so as to compensate for any crookedness in such I-beam and thickness variations in such refractories.

In the structures of my said prior patents, the refractory units supported by the sections at the fixed ends of the cantilever beams abut one against the other. In the present structure, however, such units abut against opposite side faces of the group of four refractory units located below the I-beam and which are directly engaged by the one-piece cast metal hanger member itself.

The roof structure of this invention in its preferred form comprises but two types of main refractory blocks (a) roof blocks 30 of Figs. 4 and 5 which show opposite sides of the same block and (b) hanger blocks 31 of Fig. 6.

The free ends of the aligned cantilever beams are tied together by means of metal tie members 32 (Fig. 19) and the spaces below the same and between the end refractories of the bundles supported by such cantilever beams are filled by two oppositely positioned shouldered refractory blocks 33 shown in Fig. 18.

Roof blocks

Roof blocks 30 in reality are but half blocks since they preferably are but about 5 1/4 inches

wide. They, however, have a normal length of 10 inches and a normal thickness of 3 inches.

As shown in Figs. 4 and 5, which are views of the same block showing opposite sides thereof, it will be seen that such block in one of its wide faces, is provided with a generally triangular depression 34 and on its opposite wide face with a generally triangular projection 35 of the same size, shape and relative location as such depression.

When those blocks are assembled into units with hanger blocks 31 as shown in Fig. 7 and arranged in abutting relation to form the bundles of Figs. 1 and 2, the projections 35 and depressions 34 of each such assembly will interlock with those of reverse form in opposite sides thereof.

Since the apices of these generally triangular portions 34 and 35 are disposed adjacent the tops of the blocks, the interlocking effect occasioned by the meshing of the projections and depressions of abutting blocks is as effective as the interengaging projections and depressions of the block disclosed in my Patent 2,126,901.

As an alternative construction, one wide face of each roof block can be provided with a triangular projection which in its entirety is located between and spaced from the long edges of one of the wide faces, and the opposite wide face can be provided with a depression which corresponds in shape, size and location to such projections. The form shown in the drawings, however, is preferable since it is easier to produce and therefore cheaper.

Each roof block 30 adjacent its top and immediately above the apex of depression 34 and projection 35 is so formed that when two blocks 30 are placed in abutting relation, as shown in Fig. 7, a two-part pocket is provided (half in one block and half in the other) to receive and engage the lower end of a hanger block 31.

The construction of hanger blocks 31 is preferably such that it is necessary to slide the roof blocks into engagement with the hanger blocks and to do this from opposite directions. This is so because pockets 36—36 formed in opposite long sides of hanger blocks 31 have their open ends facing in opposite directions.

Roof block 30 in its narrow side immediately above projection 35 and depression 34 is formed with two portions having faces 37 and 38 which are inwardly offset with relation to each other and to the face of the remainder or major part of the adjacent narrow face of the block, thus forming a shelf 39 and a ledge 40.

Immediately behind shelf 39, the block is provided with a downwardly extending groove 41 having a rounded bottom which connects the back of shelf 39 with the bottom of offset wall 38.

The planes of faces 37 and 38 preferably parallel the plane of the major part of the adjacent narrow face of the block. Shelf 39 and groove 41 both extend from one wide face to the opposite wide face while ledge 40, which overhangs groove 41, terminates short of the wide side face having triangular projection 35 thereon as shown at 42 (Figs. 4 and 5) for a purpose to be later described in connection with hanger block 31.

Hanger blocks

Each hanger block 31 is designed to engage and support two roof blocks 30 to form an integrated unit as shown in Fig. 7. Each of these units is suspended by a metal hanger 43 (Figs. 15, 16 and 17) which is adapted to form part of a built-up or sectional cantilever beam as disclosed

in Fig. 1 in which view three complete beams are shown, each designated 44 as an entirety.

The fixed end of each of these beams is removably attached to an upstanding hook-like anchor portion 45 of one of the one-piece cast metal hanger members 46 (Figs. 8 to 11) which is supported on the lower flange 47 of one of the overhead I-beams.

Each three-part unit suspended by a metal hanger member 43 forming part of a sectional cantilever beam 44 is hung off center as are the individual roof blocks in my said patents. From this it will be seen that each three part unit because of this off center hanging is biased toward one or the other side face of the group of four assembled integrated units located below and directly engaged by cast metal hanger members 46.

This group of units, therefore, forms an abutment for the refractories supported by each pair of opposed sectional cantilever beams.

Hanger blocks 31 for use with 3 inch thick roof blocks are preferably 3 inches square and about 8 1/4 inches long. Each such block adjacent its top is provided with both longitudinal and transverse grooves or slots in opposite sides thereof to accommodate metal hanger members 43. Longitudinal groove or slot 48 and transverse groove or slot 49 which joins the same receive leg 50 and its cross member 51. Slot 52 is provided for leg 53 of the hanger member and the lower end of slot 52 opens into a transverse slot 54 which extends through the hanger block from side to side. The back wall 55 of slot 48 is inclined as shown in Fig. 15 as in my said patents for the purpose of facilitating the placing of said hanger 43 in position on hanger block 31.

The bottom of hanger block 31 is provided with two depending bead-like flanges 56-58 which extend along opposite side edges thereof and are arranged to co-operate with or enter sub grooves 41 of the roof blocks 30. Pockets or side grooves 36 which are directly above flanges 56 are designed to receive the foreshortened ledges 40 of the two roof blocks 30 as such blocks are slid into position from opposite sides of the hanger block to the position shown in Fig. 7. Because of the fact that grooves or pockets 36 are reversely arranged, the end walls of the grooves on one hanger block 31 form closures for the open ends of grooves 36 in the abutting hanger blocks and thus prevent roof blocks 30 from sliding out of interlocking position.

Metal hanger members

Each of the one-piece cast metal hanger members 46 as above pointed out is adapted to support four three-part units such as disclosed in Fig. 7 and each comprises a body portion 57 which has a base member 58, end members 59 and a central member 60, which parallels end members 59 and is provided with an upstanding projection 61 adjacent to but spaced from its outer end as shown in Fig. 8.

Extending inwardly from opposite ends of body 57 are opposed arms 62-62 which are adapted to extend above the lower flange 47 of one of the overhead I-beams. Each arm 62 at its inner or free end is provided with a downwardly extending pad-like projection 63 which is adapted to bear on the top of the lower flange of such I-beam (Figs. 1 and 13).

Hanger member 46 can be positioned on such lower flange by tilting it (the hanger) to an un-

usual position then moving it so that one edge of such lower flange 47 of the I-beam enters the hanger opening between arms 62 and until such entering edge is located within one end 64 or 65 as the case may be of the opening between body portion 57 and arms 62, at which time the opposite edge of flange 47 can be moved through such opening. Then the hanger member can be lowered until pad-like ends 63-63 rest on the upper surface of flange 47 of the I-beam. The hanger member is then centered on such flange and the four hanger blocks 31 placed in position in such hanger member.

The two center hanger blocks 31 each with its two roof blocks assembled therewith are first placed in position within hanger member 46. This is done by so arranging such hanger blocks that the sides of such blocks which have grooves 52 and 54 therein face one another with central member 60 therebetween. The blocks are then moved into contact so that central member 60 lies within both grooves 54, and upwardly extending projection 61 lies within both grooves 52.

The outer two of the four hanger blocks 31 each with one of its roof blocks secured thereto are next entered in the hanger member 46. This is done by placing them in front of the hanger member with the side faces having grooves 54 and 52 therein facing outwardly or toward the ends of the hanger member and with grooves 54 in line with end members 59. The hanger members are then slid into place, end members 59 entering grooves 54. The other two roof blocks are then assembled with the two hanger blocks.

This arrangement of the four hanger blocks within a hanger member 46 is clearly shown in Figs. 12 and 13.

With the outer hanger blocks 31 in place, the central hanger blocks are locked in position by such outer blocks and upstanding projection 61 of central member 60.

The body of hanger member 46 is preferably reinforced by reinforcing ribs 66 which extend transversely of the body below its ends and center and are preferably tapered as shown in Figs. 10 and 11.

From Figs. 12 and 13, it will be apparent that after the hanger blocks are inserted in position within metal hanger member 46, such hanger member is anchored to the I-beam. The clearance spaces between the edges of flange 47 of the I-beam and shoulders 67 on the under sides of arms 62 of hanger member 46 permit sufficient lateral adjustment of hanger member 46 relative to the I-beam to compensate for any crookedness of such I-beam and/or thickness variations in the refractories.

In Fig. 2, I disclose six complete groups or bundles of units embodying this invention. Three of these are shown in side elevation in Fig. 1. Four of these groups of Fig. 2 are supported from the right-hand I-beam while two are supported from the left-hand I-beam.

Since all the refractory roof blocks 30 are the same—there being no rights or lefts—the blocks at the junction of the two bundles below the web of the I-beam interlock as will be apparent from Fig. 20 which is a sectional view taken on line XX-XX of Fig. 1 and embraces the major part of the roof blocks disclosed in Fig. 1.

Since the roof blocks 30 all have a triangular depression in one wide face and a corresponding projection on the opposite wide face, it follows that the opposite end of any two-block unit assembly made up wholly of blocks 30 would have

a triangular projection and a triangular depression at each end. Since it is necessary to bridge the gap between the ends of adjacent bundles of roof blocks, I have produced shouldered blocks 33 one of which is illustrated in Fig. 18. These blocks each have two wide parallel faces which in the main are flat but each of which is provided with a triangular depression 68 which is of such size and shape as to be capable of receiving or containing one of the projections 35 of roof blocks 30.

Each block 33 is provided with a head portion 69 which increases the height of this block about one inch over the height of blocks 30. For about two thirds of the distance between the long sides of this block, this head portion projects laterally beyond the wide faces about one half inch on each side forming shoulders 70. All the edges of head 69 except the side edges of shoulders 70 are chamfered as shown in Fig. 18. It will be seen that the narrow portion of head 69 lies immediately above the apices of the triangular depressions 68 which are similarly disposed in the long wide faces of these shouldered blocks.

In order that the gaps or spaces between the ends of adjacent bundles or groups of roof blocks 30 may be filled by means of these shouldered blocks 33, I have produced a roof block 71 (Fig. 20) to take the place of one of the end blocks 30 at each end of each bundle. Blocks 30 that are thus displaced are those that have their triangular depressions in the outer or end faces of the bundle.

Blocks 71 are exactly the same as blocks 30 except that instead of having a triangular depression on one side and a triangular projection on the opposite side, they have triangular projections on both side faces as disclosed in Fig. 20. It will be noted that blocks 71 are used at two diagonally positioned corners of each bundle in order to provide both ends of each bundle with a triangular projection double the area or size of the projections of roof blocks 30.

The construction and arrangement of shouldered gap sealing blocks 33 and the end blocks 30 and 71 of the bundles are such that when shoulders 70 of blocks 33 rest on top of the end blocks of two adjacent bundles, the diagonal ledges formed by the junction of depressions 68 and the wide faces of such blocks 33 overlie the combined triangular projections of end blocks 30 and 71.

The spaces between the ends of the bundles and the adjacent furnace wall may be filled with blocks 33 using two such blocks for the ends of each bundle by supporting such blocks on one side by the blocks of the bundle and on the opposite side by the top of the furnace end or side wall as the case may be, or by a ledge projecting from such wall. In order to seal those portions of the joints between the end roof blocks of two adjacent aligned bundles not covered by shoulders 70 of blocks 33, I fill the openings provided by the chamfered or beveled edges of such blocks with suitable clay 72 (Fig. 2).

The spaces 73 (Figs. 2 and 3) between adjacent rows of bundles are preferably not over $\frac{1}{8}$ of an inch wide and in order to fill and seal these, I use suitable clay.

Since the bundles are arranged in collateral courses, channels are produced between the rows of hanger blocks 31, and I prefer to place within such channels slabs or blocks of refractory material which will cover the spaces or joints 73 between such courses in a manner similar to

that disclosed in my Patent 2,125,901. I also preferably fill the spaces between such blocks or slabs and hanger blocks 31 with plastic refractory material as disclosed in such patent.

5 I prefer to use wide flange I-beams as shown in the drawings for the support beams since the inner surfaces of the flanges of such beams are flat and make the lateral shifting or adjustment of hanger members 46 with their load easier than 10 when using beams having tapered flanges.

In case it is desirable to join together the outer 15 ends of adjacent bundles for the purpose of alignment and stabilization, I prefer to use my tie member 32 disclosed in Fig. 19. This preferably 20 comprises a malleable casting provided with spaced horns 74 and spaced legs 75 braced by a 25 stiffening web 76. In utilizing tie member 32, horns 74-74 are hooked under and around shanks 77 of the hook 78 of the end hangers 43 of adjacent bundles. Tie member 32 is then 30 tilted down until in vertical position with legs 75 in contact with hanger blocks 31 suspended by hanger members 43 as disclosed in Figs. 1 and 2. Shouldered blocks 33, which bridge the gaps 35 between the ends of adjacent bundles, co-operate with members 32 in stabilizing the roof structure and particularly the ends of adjacent bundles of refractories.

Modifications

In Figs. 21 and 22, I disclose another form of one-piece cast metal hanger which can be used for supporting the oppositely extending sectional cantilever beams disclosed in Figs. 1 and 2. This hanger member is not adapted to support hanger blocks 31, but requires a special ceramic hanger block.

One of these special blocks is disclosed in Fig. 23 and an assembly of such blocks with four roof blocks 30 is disclosed in Fig. 24. Use of this special hanger block with the form of one-piece hanger shown in Figs. 21 and 22 is disclosed in Figs. 25 to 28 inclusive.

The one-piece cast metal hanger of Figs. 21 and 22 resembles hanger 46 in that it is provided with arms 79 that extend upwardly and inwardly from the ends of its body toward one another and are provided with contact pads at the inner or free ends of such arms for bearing on the upper surface of the lower flange of the I-beam. This hanger can be placed on the lower flange of an I-beam in the same manner as described in connection with hanger 46 and can also be adjusted laterally of such flange.

55 Its body portion is provided with two oppositely opening pockets each designed to receive one special refractory hanger block and each such pocket is bounded on three sides by a horizontal flange 80. This block which is numbered 81, as 60 above mentioned is disclosed by itself in Fig. 23 and in combination with four roof blocks 30 in Fig. 24.

This block 81 has a head portion 82 which is 65 rectangular in cross section as is the body of such block and is connected to the body by a neck portion formed by a groove 83 which surrounds three sides of the block. When the head portion 82 of such block is placed within one of the pockets of this hanger member, with its side 84 facing outwardly of such pocket, flange 80 will 70 lie within groove 83 and surround three sides of the block.

The bottom of hanger block 81 is provided 75 with downwardly extending bead-like flanges along its opposite long edges similar to flanges 56

of hanger block 31 and these are adapted to co-operate with the grooves in roof blocks 30 in the same manner as flanges 56. The lower portion of this hanger block is provided with oppositely positioned grooves 85 and 86 for receiving ledges 39 of four roof blocks 30 as disclosed in Fig. 24. Groove 85 extends throughout the full width of the hanger block while groove 86 terminates short of end 87 of such block so that ledges 39 of two of the roof blocks of the assembled group shown in Fig. 24 have to be entered into groove 86 from the opposite end of the block from end 87.

This application is a continuation in part of a copending application filed by me on October 27, 1947, Serial No. 782,339, which application has now become abandoned.

What I claim is:

1. A refractory unit for use in constructing furnace roofs, comprising an elongated ceramic hanger member of substantially square cross section and two roof blocks interlocked therewith and each having two wide and two narrow sides; such hanger member adjacent its lower end having pockets in two of its opposed long sides; each such pocket having an open end which is located in one of the other long sides of the hanger member, each roof block having a ledge formed in one of its narrow sides adjacent its top, such hanger member on its lower end and paralleling the planes of its pocketed long sides having two spaced parallel downwardly extending bead-like flanges; each roof block below and in the same narrow side in which its ledge is located having an open top groove which parallels the bead-like flanges of the hanger member and extends from one of its wide sides to its other wide side; the ledge of each roof block being adapted to slide into one of the hanger member pockets through its open end as one of the bead-like flanges of the hanger member is slid lengthwise into the open top groove located below such ledge.

2. A refractory unit for use in constructing furnace roofs, comprising an elongated ceramic hanger member of generally rectangular form and two roof blocks interlocked therewith and each having two wide and two narrow sides, such hanger member adjacent its lower end having pockets in two of its opposed long sides; each such pocket having an open end which is located in one of the other long sides of the hanger member; such hanger member on its lower end below such pockets and paralleling the planes of such pocketed long sides having a pair of spaced parallel downwardly extending bead-like flanges; each roof block adjacent its upper end being formed with an open top groove in one narrow side thereof which parallels the bead-like flanges of the hanger member and having a ledge above such groove adapted to slide into one of the said hanger member pockets through its open end as such bead-like flange is slid lengthwise to position within one such groove.

3. A refractory unit for use in constructing furnace roofs, comprising an elongated ceramic hanger member which is generally square in cross section and two roof blocks interlocked therewith and each having two wide and two narrow sides, such hanger member adjacent its lower end having pockets in two of its opposed long sides; such pockets having at least one open end which is located in one of the other long sides of the hanger member, such hanger member on its lower end below such pockets and paralleling the planes of its pocketed long sides

having a pair of spaced parallel downwardly extending bead-like edge flanges; each such roof block in a narrow side thereof adjacent its upper end being formed with an open top groove which parallels the bead-like flanges of the hanger member and extends from one of its wide sides to the other wide side for slidably receiving one such bead-like flange and having a ledge above such groove adapted to slide lengthwise into one of the hanger member pockets through its open end as such bead-like flange is slid lengthwise to position within such groove.

4. A ceramic hanger member designed to support two furnace roof blocks each having two wide and two narrow sides, such hanger member comprising an elongated refractory block which in the main is square in cross section, and which adjacent the lower end of each of two of its opposed long sides is provided with a pocket having at least one open end which is located in one of the other long sides of the hanger member and on its lower end below such pockets is provided with a pair of spaced downwardly extending parallel bead-like flanges which parallel the planes of its pocketed long sides and serve as downward extensions of such long sides.

5. A ceramic hanger member designed to support two furnace roof blocks each having two wide and two narrow sides, such hanger member comprising an elongated refractory block which in the main is rectangular and which adjacent the lower end of each of two of its opposed long sides is provided with a pocket having an open end; the open ends of such pockets facing in opposite directions and being located in the other opposed long sides of the hanger member in order to slidably receive from opposite directions ledge-like portions formed in one of the narrow sides of such roof blocks; such hanger member on its lower end below such pockets being provided with a pair of spaced downwardly extending parallel bead-like flanges which parallel the planes of said pocketed long sides; each such bead-like flange being arranged to slide lengthwise into an open top groove which parallels such bead-like flanges and is formed in one narrow side of one of such roof blocks as the ledge-like portion of such roof block which overhangs such open top groove is slid lengthwise into one of such hanger member pockets through its open end.

6. The combination with a horizontally extending I-beam in which the lower flange thereof is provided with flat upper surfaces on opposite sides of the beam web, of a metal hanger member having opposed arms which embrace such flange and which, adjacent their free ends, are provided with downwardly extending pad-like projections which bear on the top surface of such flange and hold such arms above and in spaced relation thereto so as to permit movement of such hanger member laterally of such beam without tilting; such hanger member being further provided with means located below such lower flange for supporting multiple ceramic hanger blocks and having hook engageable anchor portions at its opposite ends which extend upwardly above such flange.

7. The combination with an overhead I-beam having wide flat flanges, of a metal hanger member mounted on and shiftable laterally of the lower flange of such beam; such hanger member having anchor portions adjacent its opposite ends, having pockets, the walls of which are provided with means for engaging the walls of grooves of

ceramic hanger blocks, ceramic hanger blocks located within such pockets and having groove walls engaged by such means, refractory roof blocks engaged by and depending from such hanger blocks, sectional cantilever beams extending in opposite directions from such I-beam and having their fixed ends removably attached to such anchor portions, a ceramic hanger block engaged by and depending from each section of such cantilever beams and refractory roof blocks engaged by and depending from each such hanger block.

8. The combination with an overhead I-beam having wide flat flanges, of a metal hanger member having arms positioned above the lower flange of such beam and being formed with means resting on the upper surface of such lower flange for holding such arms above and out of contact with such flange except for such means to facilitate the shifting of such hanger member laterally of such beam; such hanger member having anchor portions adjacent its opposite ends and pockets, the walls of which are provided with means for engaging grooves of four ceramic hanger blocks, four ceramic hanger blocks located within such pockets and having groove walls engaged by such means, refractory roof blocks engaged by and depending from such hanger blocks, sectional cantilever beams extending in opposite directions from such I-beam and having their fixed ends removably attached to such anchor portions, a ceramic hanger block engaged by and depending from each section of such cantilever beams and refractory roof blocks engaged by and depending from each such hanger block.

9. The combination with an overhead I-beam having wide flat flanges, of a metal hanger member having arms positioned above the lower flange of such beam and being formed with means resting on the upper surface of such lower flange for holding such arms above and out of contact with such flange except for such means to facilitate the shifting of such hanger member laterally of such beam; such hanger member having anchor portions adjacent its opposite ends and pockets, the walls of which are provided with means for engaging walls of grooves of ceramic hanger blocks, ceramic hanger blocks located within such pockets and having groove walls engaged by such means, refractory roof blocks engaged by and depending from such hanger blocks, sectional cantilever beams extending in opposite directions from such I-beam and having their fixed ends removably attached to such anchor portions, a ceramic hanger block engaged by and depending from each section of such cantilever beams and refractory roof blocks engaged by and depending from each such hanger block.

10. The combination with an overhead I-beam having wide flat flanges, of a metal hanger member having arms positioned above the lower flange of such beam and being formed with downwardly extending pad-like members resting on the upper surface of such lower flange for holding such hanger member arms above and out of contact with such flange except for such pad-like members to facilitate the shifting of such hanger member laterally of such beam; such hanger member having anchor portions adjacent its opposite ends and two pockets, the walls of which are provided with means for engaging grooves of ceramic hanger blocks, ceramic hanger blocks located within such pockets and having groove walls engaged by such means, refractory roof blocks engaged by and depending from such

hanger blocks, sectional cantilever beams extending in opposite directions from such I-beam and having their fixed ends removably attached to such anchor portions, a ceramic hanger block engaged by and depending from each section of such cantilever beams and refractory roof blocks engaged by and depending from each such hanger block.

11. The combination with an overhead I-beam, 10 of a metal hanger mounted on and shiftable laterally of the lower flange of such beam, having anchor portions adjacent opposite ends thereof and pockets adjacent its bottom for receiving two ceramic hanger blocks, two ceramic hanger blocks 15 having portions thereof located within such pockets, refractory roof blocks engaged by and depending from such ceramic hanger blocks, cantilever beams extending in opposite directions from such I-beam and having their fixed ends 20 removably attached to such anchor portions, a plurality of ceramic hanger blocks carried by and depending from such cantilever beams and refractory roof blocks engaged by and depending from such ceramic hanger blocks.

12. The combination with an overhead I-beam, 25 of a metal hanger mounted on and shiftable laterally of the lower flange of such beam, having anchor portions adjacent opposite ends thereof, having means for limiting lateral movement between it and such flange and having pockets adjacent its bottom for receiving two ceramic hanger blocks, two ceramic hanger blocks having parts thereof located within such pockets, four refractory roof blocks engaged by and depending 30 from such ceramic hanger blocks, cantilever beams extending in opposite directions from such I-beam and having their fixed ends removably attached to such anchor portions, a plurality of ceramic hanger blocks carried by and depending from such cantilever beams and refractory roof blocks engaged by and depending from such ceramic hanger blocks.

13. The combination with an overhead I-beam, 45 of a one-piece metal hanger mounted on and shiftable laterally of the lower flange of such beam, having anchor portions adjacent opposite ends thereof and pockets adjacent its bottom for receiving two ceramic hanger blocks, two ceramic hanger blocks having parts located within such pockets, four refractory roof blocks engaged by and depending from such ceramic hanger blocks, cantilever beams extending in opposite directions from such I-beam and having their fixed ends 50 removably attached to such anchor portions, a plurality of ceramic hanger blocks carried by and depending from such cantilever beams and refractory roof blocks engaged by and depending from such ceramic hanger blocks.

14. The combination with a horizontal I-beam, 60 of a one-piece metal hanger embracing the lower flange of such beam and shiftable laterally thereof; such hanger having anchor portions at its opposite ends above such flange and below such flange having two oppositely opening pockets arranged side by side for receiving parts of two ceramic hanger blocks, portions of two ceramic hanger blocks located within and depending below such pockets, two cantilever beams extending in opposite directions from such I-beam and having their fixed ends removably attached to such anchor portions, ceramic hanger blocks carried by such cantilever beams, and a plurality of refractory roof blocks interengaged by and depending from each ceramic hanger block.

15. The combination with an overhead I-beam

having wide flat flanges, of a cast metal hanger member having a body portion, end portions offset from such body portion, arms extending inwardly from such end portions for embracing the lower flange of such beam and at their free ends being provided with downwardly extending pad-like members for resting on the upper surface of such flange and for spacing such arms, except for such pad-like members, above such flange, a central member extending from the bottom portion of such body and with such end members forming two pockets on the same side of such body portion, such end members and such central member having means for engaging the walls of grooves of ceramic hanger blocks, ceramic hanger blocks located within such pockets and having groove walls engaged by such means, and refractory roof blocks engaged by and depending from such hanger blocks.

16. The combination with an overhead I-beam having wide flat flanges, of a cast metal hanger member having a body portion, end portions offset from such body portion, arms extending inwardly from such end portions for embracing the lower flange of such beam and at their free ends being provided with downwardly extending pad-like members resting on the upper surface of such flange and spacing such arms, except for such pad-like members, above and out of contact with such flange, a central member extending from the bottom portion of such body, and with such end members, forming two pockets on the same side of such body portion; such end members and such central member having means for engaging

walls of grooves of four ceramic hanger blocks, four ceramic hanger blocks located within such pockets and having groove walls engaged by such means, and refractory roof blocks engaged by and depending from such hanger blocks.

- 5 17. The combination with an overhead I-beam having wide flat flanges, of a cast metal hanger member having a body portion, end portions offset from such body portion, arms extending inwardly from such end portions embracing the lower flange of such beam and at their free ends being provided with downwardly extending pad-like members resting on the upper surface of such flange and spacing such arms, except for such pad-like members, above and out of contact with such flange, a central member extending from the bottom portion of such body and with such end members forming two pockets on the same side of such body portion; such end members and such central member having means for engaging walls of grooves of four ceramic hanger blocks.
- 10 18. The combination with an overhead I-beam having wide flat flanges, of a cast metal hanger member having a body portion, end portions offset from such body portion, arms extending inwardly from such end portions embracing the lower flange of such beam and at their free ends being provided with downwardly extending pad-like members resting on the upper surface of such flange and spacing such arms, except for such pad-like members, above and out of contact with such flange, a central member extending from the bottom portion of such body and with such end members forming two pockets on the same side of such body portion; such end members and such central member having means for engaging walls of grooves of four ceramic hanger blocks.
- 15 19. The combination with an overhead I-beam having wide flat flanges, of a cast metal hanger member having a body portion, end portions offset from such body portion, arms extending inwardly from such end portions embracing the lower flange of such beam and at their free ends being provided with downwardly extending pad-like members resting on the upper surface of such flange and spacing such arms, except for such pad-like members, above and out of contact with such flange, a central member extending from the bottom portion of such body and with such end members forming two pockets on the same side of such body portion; such end members and such central member having means for engaging walls of grooves of four ceramic hanger blocks.
- 20 20. The combination with an overhead I-beam having wide flat flanges, of a cast metal hanger member having a body portion, end portions offset from such body portion, arms extending inwardly from such end portions embracing the lower flange of such beam and at their free ends being provided with downwardly extending pad-like members resting on the upper surface of such flange and spacing such arms, except for such pad-like members, above and out of contact with such flange, a central member extending from the bottom portion of such body and with such end members forming two pockets on the same side of such body portion; such end members and such central member having means for engaging walls of grooves of four ceramic hanger blocks.

LEVI S. LONGENECKER.
